Primary Examiner — Calvin E Vansant*Assistant Examiner* — Eidiol Ghigliotti Torres(74) *Attorney, Agent, or Firm* — UB Greensfelder LLP;
Brian E. Turung(57) **CLAIM**

The ornamental design for a pump system housing, as shown and described.

DESCRIPTION

FIG. 1 is a front perspective view of a pump system housing in accordance with the new design;

FIG. 2 is a front plan view of the pump system housing of FIG. 1;

FIG. 3 is a back plan view of the pump system housing of FIG. 1;

FIG. 4 is a first side plan view of the pump system housing of FIG. 1;

FIG. 5 is a second side plan view of the pump system housing of FIG. 1;

FIG. 6 is a top plan view of the pump system housing of FIG. 1;

FIG. 7 is a bottom plan view of the pump system housing of FIG. 1; and,

FIG. 8 is a bottom perspective view of a pump system housing in accordance with the new design.

In the drawings, the broken lines depict portions of the pump system housing that form no part of the claimed design.

1 Claim, 8 Drawing Sheets(56)
